UNITED STATES PATENT OFFICE.

WILLIAM F. GATEWOOD, OF PIERCE CITY, MISSOURI, ASSIGNOR OF ONE-THIRD TO ETHELBERT P. LAMPKIN, OF ST. LOUIS, MISSOURI, AND ONE-THIRD TO WILLIAM W. LOCKE, OF PIERCE CITY, MISSOURI.

PRINTING MECHANISM FOR ADDING-MACHINES.

No. 875,343.

Specification of Letters Patent.

Patented Dec. 31, 1907.

Original application filed June 18, 1906, Serial No. 322,138. Divided and this application filed February 4, 1907, Serial No. 355,618.

To all whom it may concern:

Be it known that I, WILLIAM F. GATEWOOD, a citizen of the United States of America, residing in Pierce City, in the county of Lawrence and State of Missouri, have invented certain new and useful Improvements in Printing Mechanisms for Adding-Machines, of which the following is a full, clear, and exact description, reference being had to the accompanying drawings, forming part of this specification.

My invention relates to an improvement in printing mechanisms for that character of adding machines utilized for performing addition and also for recording the result of the adding mechanism the present application being a division of an application filed by me June 18th, 1906, Serial Number 322,138.

Figure I is a side elevation of the adding machine, containing my improvements. Fig. II is in part, a top or plan view of the machine with certain parts of the mechanism shown in horizontal section. Fig. III is an inverted plan view of the machine. Fig. IV is a longitudinal section through the machine. Fig. V is an enlarged longitudinal section through the central and rear part of the machine. Fig. VI is a view partly in plan and partly in horizontal section taken on line VI, VI, Fig. V.

1 designates the base of my machine, which is provided with a bottom flange 2 and in which, near its forward end, is a transverse slot 5 and near the rear end a transverse slot 7. The base supports a carriage that is reciprocally mounted thereon and comprises upright side bars 11 connected by a spacing rod 13, and a series slotted guide posts 17. The carriage side bars are provided with forwardly extending horizontal arms 21 and rearwardly extending horizontal arms 22.

23 are item wheels each of which bears upon its periphery the numerals "1 to 9" and the "0" sign.

45 Each item wheel bears at its side, pins 24, corresponding in number to the number of characters upon the periphery of the wheel and the entire series of item wheels is loosely mounted upon a supporting shaft 25, seated 50 in the horizontal carriage side bar arms 21.

26 are type wheels of a number equal to that of the item wheels, and each of which bears at its periphery type characters corresponding to the characters borne by said

item wheels. The type wheels are supported in alinement with the item wheels and loosely mounted upon the supporting shaft 27, seated in the rear horizontal arms 22, of the carriage side bars. At one side of each type wheel are pins 28 corresponding in number to the number of characters on the wheel.

29 are drop rack bars, each of which is provided with rack teeth at both its edges to engage the pins of the item wheels and type wheels. The rack bars are supported by the reciprocating carriage previously mentioned.

89 designates a pair of standards mounted upon the rear portion of the base of the machine.

90 is a paper reel journaled to a frame 85 and adapted to contain a ribbon A of paper on which the items of addition are printed from the type wheels 26. The reel is controlled in its rotation by a spring brake 91 that is attached to one of the standards 89 and bears against one end of the reel, the desired tension upon the spring brake being secured by an adjustment screw 92. 93 are posts surmounting the standards 89.

94 are paper feed rollers having shafts journaled in the posts 93 to which the paper is delivered from the reel 90. In passing to the rollers the ribbon of paper travels in a course in juxtaposition to the type wheels 26.

95 designates a plurality of roller platens that are arranged in opposition to the type wheels 26 and by which the ribbons of paper is carried to the characters on said type wheels for the purpose of causing impressions to be made on the paper by the type. The roller platens are carried by slide bars 96 extending longitudinally of the machine (see Figs. I, IV, V and VI). The slide bars are mounted in a frame supported by the standards 89 and having a forward slotted wall 97 and a rear slotted wall 98 in which the bars operate, the slots in the forward wall being of greater height than the slots in the rear wall, in order that said bars may be held in inclined positions with their front ends highest. The slots in the forward wall 97 are of a sufficient vertical length to permit of an upward movement of the platen carrying bars when they are pressed forward in the manner to be presently explained, in order that the roller platens will rotate against the face of the type of the type wheels while performing the

printing action, and thereby produce a more perfect impression upon the paper, due to a more gradual pressure against the type. 5. The rearward movement of the platen carrying bars is restricted by stop pins 99 that are seated in said bars and are adapted to engage the forward frame wall 97.

100 are end walls of the platen carrying bar frame and 101 is a cross rod mounted in these end walls. 102 are spring fingers that extend over the roller platen bars and terminate in juxtaposition to the upper edges of said bars as seen in Fig. V. These springs 15 are adapted to resist the upward movement of said bars in a yielding manner, in order that the roller platens may be held firmly, yet yieldingly, against the type of the type wheels during their rising movement in printing action. 20

103 designates a bumper frame pivoted at 104 to the standards 89 and having a slotted cross head 105 at its outer end. This bumper frame is adapted to be elevated to the rear 25 side of the frame in which the platen bars are located and the slots in its cross-head are of sufficient dimensions to permit the rear projecting ends of said platen carrying bars passing through them except when said slots are 30 guarded in the manner to be hereinafter explained.

106 is a rear guide strip secured to the cross head of the bumper frame.

107 are forward guide strips (see Figs. 35 II and IV) that are secured to the arms of the bumper frame.

108 are bumper slides which correspond in number to the number of roller platen bars and which are loosely positioned between the 40 guide strips 107 and the bumper frame cross head 105 and guide strip 106 to be guided thereby during their sliding movement. These bumper slides are provided with stop pins 109 and 110 (see Figs. III and IV) 45 which are adapted to strike respectively against one of the guide strips 107 and against the bumper frame cross head 105 to restrict the movement of the slides. The bumper slides are adapted to be moved rearwardly by 50 means to be hereinafter described, for the purpose of causing their rear ends to close the slots in the bumper frame cross head in order that said slides will strike against any desired number of the roller platen bars 96 55 when the bumper frame is elevated into a vertical position.

111 is a brake bar pivoted to the bumper frame and extending across the bumper slides, the said brake bar being preferably 60 provided at its rear side with a rubber or other facing strip 112 which by bearing against the bumper slides will create sufficient friction between said parts to prevent retrograde movement of the bumper slides 65 in a forward direction while they are being

elevated with the bumper frame to strike the platen bars.

113 is a cam that is arranged immediately in front of the bumper mechanism of the machine and which is provided with a leg 70 114 that operates in the slot 7 of the base 1, as seen in Figs. II, III, IV and V. This cam is adapted to be moved transversely of the base of the machine for the purpose of causing it to engage against the inner ends of the 75 bumper slides 108 and throw them rearwardly to close the slots in the bumper frame cross head in the manner stated.

115 is a lever pivoted at 116 to the case of the machine (see Figs. III and IV). The 80 rear arm of this lever is provided with a stem 117 loosely seated in the leg of the cam 113. The forward arm of the lever is provided with a stem 118 loosely seated in the leg 49 of the spacing plate 47. 85

It will be seen that when the spacing plate is moved to the desired distance in the operation of the machine, the lever 115 will be actuated thereby and will in turn impart movement to the cam 113 for the purpose of moving a number of the bumper slides 108 rearwardly to close the slots in the bumper frame cross head and that the number of bumper slides so moved will correspond to the degree of movement of the spacing plate. 95

119 designates a pull rod by which the bumper frame 103 is elevated. This pull rod has a bifurcated rear end 120 which straddles a leg of a standard 89 by which said bar is guided. One arm of the bifurcated end of 100 the rod 119 is provided with a notch 121 which provides a shoulder in said arm. The shoulder is adapted to engage a stud 122 projecting from the adjacent side of the bumper frame (see Fig. II) so that when the pull rod 105 is moved forwardly the bumper frame will be elevated to a vertical position for the purpose of carrying the bumper slides that have been projected rearwardly, into impact with the projecting rear ends of the roller platen bars 110 96. Each bumper slide projected is thereby caused to strike against the companion platen bar to move said bar toward the corresponding type wheel and cause an impression of the type of said wheel presented toward said platen to be made upon the ribbon A of paper through an ink ribbon to be more particularly mentioned. 123 is a lever pivoted to a post 124 mounted on the base of the machine. This lever is pivotally connected at 125 to the pull rod 119. When the lever is moved rearwardly the notch 121 of the pull rod receives the stud 122, and when the lever is moved forwardly the shoulder at the rear end of said notch engages said stud 125 for the purpose of lifting the bumper frame, and as the bumper frame reaches the limit of its upward movement and strikes the frame wall 98 a jar is occasioned, due to which the pull rod is shaken from the stud 122, thereby 130

- permitting the bumper frame to immediately resume its normal position. Located at the opposite side of the machine from that at which the bumper frame actuating mechanism is located, is a spool (not shown) that is rotatably mounted on a suitable support, and has connected to it one end of an ink ribbon 130. The ink ribbon extends transversely of the machine between the type 5 wheels 26 and the roller platens 95 and immediately in front of the ribbon of paper delivered from the reel 90 to the feed rollers 94, the ribbon being directed in its travel by guide stems or rollers 131 (see Figs. I and IV).
- 10 13 The ink ribbon leads to a spool 132 which is provided with slot and pin connection with a vertical shaft 133 that is loosely mounted in a bracket 134. The shaft 133 has fixed to it a ratchet wheel 135. 136 is a lever pivoted 15 at 137 to the standard 89 adjacent to the pull rod 119 and with which pull rod said lever has slot and pin connection at 138 (see Fig. I). 139 is a pawl pivoted to the upper arm of the lever 136 and adapted to engage the 20 ratchet wheel 135 of the shaft 133 which carries the ribbon spool 132, whereby upon each rearward movement of said pull rod, rotation is imparted to the ribbon spool shaft to wind the ink ribbon thereon.
- 25 140 is a spring restraining arm attached to the bracket that supports the ink ribbon spool 132, and which by engaging with the ratchet wheel 135 serves to prevent retrograde rotation of said spool. The upper 30 part of feed roller 94 is provided with a feed wheel 141 and the lower paper feed roller is provided with a feed wheel 142, these wheels being arranged in mesh with each other.
- 35 143 is a spring controlled pawl carried by the upper arm of the lever 136 and arranged to engage the teeth of the feed wheel 142, the pawl being so applied to the lever that it will move freely beneath said feed 40 wheel when the upper arm of the lever is moved rearwardly and be restrained from swinging motion when said lever arm is again moved forwardly, whereby the pawl is caused to operate said feed wheel to rotate the feed rollers for paper feeding action.
- 45 144 is a spring stop arm which engages the upper feed wheel 141 to restrain the feed rollers from retrograde rotation.
- 50 145 is a knob fixed to the shaft of the lower feed roller 94 and by which the feed rollers 55 may be rotated in introducing the ribbon of paper between them.
- I claim:
1. In an adding machine printing mechanism, a type member, means for operating 60 said type member, a roller platen arranged for movement toward said type member, and means causing a forward and upward movement for operating said roller platen, so as to cause it to roll against the type of the 65 type member, substantially as set forth.
2. In an adding machine printing mechanism, a type wheel, means for operating said wheel, a roller platen arranged for movement toward said type wheel, and means causing a forward and upward movement 70 for operating said roller platen so as to cause it to roll against the type of the type wheel, substantially as set forth.
3. In an adding machine printing mechanism, a type wheel, means for operating 75 said type wheel, a reciprocally supported roller platen arranged for movement toward said wheel, and means for imparting a forward and upward movement to said roller platen, so as to cause it to roll against the type of the 80 type wheel, substantially as set forth.
4. In an adding machine printing mechanism, a type wheel, means for operating said wheel, a roller platen arranged for movement toward said wheel, means for imparting a forward and upward movement to said roller platen, and a support for said platen arranged so as to direct its movement at an angle to the axis of said type wheel and cause it to roll against the type of the type wheel, 85 substantially as set forth.
5. In an adding machine printing mechanism, a type wheel, means for operating said type wheel, a slide bar, a roller platen carried by said slide bar, means for moving 90 said slide bar forward and upward, so as to cause the roller platen to roll over the type of the type wheel and a spring bearing against one of the faces of said slide bar, substantially as set forth.
- 100 6. In an adding machine printing mechanism, a type member, a platen arranged for movement toward said type member, a slide bar by which said platen is carried, a swinging bumper frame, and a bumper slide fitted to said frame and adapted to be moved into impact with said platen slide bar, substantially as set forth.
- 105 7. In an adding machine printing mechanism, a type member, a platen arranged for movement toward said type member, a slide bar by which said platen is carried, a bumper frame provided with a slotted cross-head, a bumper slide loosely mounted in said frame, means for shifting said slide into a position 110 to close the slot in said cross-head, and means for elevating said bumper frame to cause said bumper slide to strike against said platen slide bar, substantially as set forth.
- 115 8. In an adding machine printing mechanism, a type member, a platen arranged for movement toward said type member, a slide bar by which said platen is carried, a bumper frame provided with a slotted cross-head, a bumper slide loosely mounted in said frame, means for shifting said slide into a position 120 to close the slot in said cross-head means for elevating said bumper frame to cause said bumper slide to strike against said platen 125 130

slide bar, and a brake carried by said frame and adapted to bear against said bumper slide, substantially as set forth.

9. In an adding machine printing mechanism, the combination of a type wheel, means for operating said type wheel, a platen, means by which said platen is carried, a bumper frame, a series of bumper slides loosely fitted in said frame and adapted to be

elevated to said platen carrying means, a cam arranged to engage said bumper slides, a spacing member, and a lever connecting said spacing member to said cam, substantially as set forth.

WM. F. GATEWOOD,

In presence of:—

FRANK J. THIELEN,
FLORENCE McNAMARA.
